(57) **CLAIM**

The ornamental design for a generator, as shown and described.

DESCRIPTION

FIG. 1 is a front elevational view of a generator showing our new design;

FIG. 2 is a back elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a front, top, left side perspective view thereof; and,

FIG. 8 is a back, top, right side perspective view thereof.

The broken lines shown in the drawings represent portions of the generator that form no part of the claimed design.
